Patented Apr. 11, 1922.

UNITED STATES PATENT OFFICE.

GEORGE WASHINGTON PAYNE, OF SPOKANE, WASHINGTON.

LACING DEVICE.

1,412,486.

Specification of Letters Patent. Patented Apr. 11, 1922.

Application filed October 6, 1920. Serial No. 414,949.

To all whom it may concern:

Be it known that I, GEORGE WASHINGTON PAYNE, a citizen of the United States, and a resident of Spokane, in the county of Spokane and State of Washington, have invented certain new and useful Improvements in Lacing Devices, of which the following is a specification.

The present invention relates in general to 10 lacing devices, and more particularly to lacing devices especially adapted for use with shoes or the like.

The object of the invention is to provide a 15 lacing device which, when associated with a shoe or the like, will serve to neatly and firmly secure the flaps of the shoe together and which provides a double expansion so that the flaps of the shoe may be loosened and the shoe may be put on and removed 20 without the necessity of removing or unthreading the lacing.

Another object of the invention is to provide a device of this character of extremely 25 simple and durable construction, which may be readily embodied in the shoe or other article to be laced and which is inexpensive to manufacture and easy to manipulate by the wearer.

Other objects and advantages of the invention reside in certain novel features of 30 construction, combination and arrangement of parts which will be hereinafter more fully described and particularly pointed out in the appended claim, reference being had to 35 the accompanying drawings forming part of this specification and in which,—

Figure 1 is a front elevational view, showing the lacing device embodied in a shoe;

Figure 2 is a horizontal sectional view on 40 line 2—2 of Figure 1;

Figure 3 is a detail view in section of one form of fastening device;

Figure 4 is a similar view in front elevation;

Figure 5 is a detail view of one form of 45 end securing device for the lacing; and

Figure 6 is a similar view of a modified form.

Referring to the drawings wherein I have 50 shown my invention embodied in a shoe, the shoe is designated generally at A, and includes an upper embodying a pair of flaps, designated at B and C respectively. An inner tongue D is arranged beneath and between the flaps B and C and secured at its lower end to the shoe. The tongue D has the

protective functions of the ordinary tongue of the shoe.

An outer tongue or flap 10 is provided and preferably is secured at its lower end 60 to the inner tongue D. The tongue 10 constitutes an intermediate flap for the pair of flaps of the upper and lies between the flaps B and C and is substantially coincident therewith.

A row of eyelets or similar fastening devices is arranged along each edge of each of the flaps B and C of the upper and are designated at 11 and 12, respectively. A row of similar eyelets or fastening devices is provided along each side edge of the flap 10, as designated at 13 and 14, respectively. The eyelets 11 of the flap B and the eyelets 13 of the flap 10 as well as the eyelets 12 of the flap C and the eyelets 14 of the flap 10 are 75 adapted to coact in the lacing operation.

A lacing 15 is reeved through the eyelets of the rows 11 and 13 and 12 and 14. As shown in the drawings preferably a single lacing is employed for the two pairs of rows 80 but if desired two lacings may be employed. As shown, the run 15^a of the lacing 15 extends alternately through the eyelets of the rows 11 and 13 and the run 15^b of the lacing 15 extends alternately through the eyelets 85 of the rows 12 and 14.

At the upper end of the tongue there are provided suitable end securing devices which are adapted to receive and secure the ends of the lacing. The devices 16 may be constructed as shown in Figure 5, with a V-shaped slot 16^a or they may be constructed as shown in Figure 6 and consist simply of a pair of eyes 16^b.

In lieu of the eyelets which constitute the 95 rows 11, 12, 13 and 14 studs may be employed. The studs to be employed in the present invention consist of a frame 17 having integral prongs 18 which secure the frame to the flaps to be laced. A pintle 19 100 is journaled in the frame 17 and a roller 20 is mounted upon the pintle 19.

In the use of the lacing device, the lacing is first inserted at the lower end of the intermediate flap and reeved through the eyelets, studs, or other fastening devices until the free ends of the lacing are positioned at the upper end of the upper of the shoe. When it is desired to place the shoe upon the foot, both runs 15^a and 15^b of the lacing are 110 loosened and this double expansion permits of the placing of the shoe upon the foot with-

2
out the necessity of removing the lacing or a portion thereof. After the shoe has been placed upon the foot the runs of the lacing are tightened so as to draw the flaps B and C and the intermediate flap 10 into edge to edge relation which firmly and neatly secures the flaps together and the shoe upon the foot. The ends of the lacing are then arranged in and retained by the end securing devices 16. The ordinary tongue D at this time exercises its protective functions, and by securing the lower end of flap 10 to this tongue, the side flaps will be drawn together evenly during the lacing up process. 15 When it is desired to remove the shoe the ends of the lacing are removed from the end securing devices and the runs 15^a and 15^b of the lacing are loosened and the shoe may be easily removed without removing any portion 20 of the lacing.

If desired the end securing devices 16 may be omitted and the ends secured by the conventional bow knot into which the ends of the lacing are tied. It is further to be under-

stood that either a single lacing doubled 25 midway and starting from the lower ends of the flaps of the shoe and lacing each side respectively, or two lacings serving to separately secure each side may be employed as desired, but the single lace is preferred. 30

I claim:

A lacing device for shoes and the like, comprising in combination with the side flaps thereof and a tongue lying beneath and between the front edges of said side flaps, 35 an intermediate filling flap adapted to be arranged loosely between the front edges of the side flaps, and secured at its lower end to the aforesaid tongue and adapted to occupy a plane coinciding with the plane of the side 40 flaps, the side edges of the intermediate flap and the adjacent front edges of the side flaps having similar lacing receiving openings and a lacing cord reeved through the adjacent 45 openings of the intermediate flap edges and side flap edges.

GEORGE WASHINGTON PAINE.
